UNITED STATES PATENT OFFICE.

HENRY W. O'NEILL, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed October 31, 1923. Serial No. 671,871.

To all whom it may concern:

Be it known that I, HENRY W. O'NEILL, a citizen of the United States of America, residing at Brooklyn, in the county of Kings 5 and State of New York, have invented certain new and useful Improvements in Telephone Systems, of which the following is a full, clear, concise, and exact description,

This invention relates to telephone systems and more particularly to systems for automatically establishing connections in the handling of toll traffic.

The principal object of this invention is to provide an improved system whereby 15 machine switching operations may be more expeditiously, reliably and economically carried out over transmission lines such as telephone toll circuits.

A feature of this invention relates to the 20 employment of one or more alternating currents to form a single impulse interval for transmission over a line circuit to effect control of switching equipment on the well known numerical impulse basis.

25 Another feature of the invention resides in an interrelation of equipment at a control or sending point relative to equipment at a distant switching point, whereby successive impulses of alternating current may 30 be released from the sending point only following reception of a reverting impulse of alternating current released from the switching or translating point.

A further feature of this invention 35 relates to the employment of alternating currents for the control of supervisory signals on the so-called positive supervision basis in a manner to render voice currents ineffective with such signals, and to the further employment of such currents in a manner to 40 place the breaking down of a connection entirely under control of an originating operator.

A still further feature of the invention 45 relates to coordination of equipment in such a manner that the first impulse of any code of impulses performs a dual function in that it first conditions the receiving system for the reception of impulses, and then, following such conditioning said first impulse and subsequent impulses are translated into impulses to control switching or selective operations.

An additional feature of the invention 55 relates to an arrangement whereby equip-

ment, in association with a toll or long distance line at a switching point thereon, may in effect, be substituted for an automatic subscriber's station associated with substantially any form of automatic switching 60 equipment to control said automatic switching equipment.

A further additional feature of this invention relates to provision for so-called two-way service or operation relative to the 65 completion of connections in either direction over a line circuit.

Another additional feature of the invention provides that a signal corresponding with so-called dialing tone must emanate 70 from inward automatic switches following seizure thereof, before waiting impulses may be released to effect response of such switches.

Other features of the invention will here- 75 inafter appear.

In carrying out the present invention, a system of keys commonly referred to as numerical or digit keys is provided at an originating toll position. By actuating 80 these keys in any predetermined order, a control operator may write or record any desired code whereby resulting operations automatically carried out may extend a connection from an associated link or cord circuit to any desired distant point or telephone station.

A system of relays, coordinated on the plan commonly referred to as counting relays, in association with the numerical 85 keys, are controlled by reverting impulses of alternating current released from a switching point on a line circuit in such a manner that impulses formed of alternating current, at a single frequency or permutations of 90 currents of different frequencies, as may have been selected under control of the numerical keys, may be released from an originating position to traverse a line circuit.

At a switching or inward point on a line, devices or circuit tuned for respective reception of incoming impulses of alternating currents of different frequencies, effect selection in a first group of relays to, in turn, establish respective predetermined "set- 100 105 110 ings" or selections in a system of counting relays from which corresponding numbers of impulses may be released to cause current changes in a loop circuit whereby the control of automatic switches may be effected.

In establishing a connection, the first impulse of alternating current from an originating point initiates switching operations to transfer a loop circuit extending to machine switching equipment, from the toll line to paths under control of the last mentioned counting relays. The first effect of such circuit transfer is to close the loop circuit and thereby initiate preliminary responses in the machine switching equipment whereby such equipment will be conditioned for the reception of selective impulses. As concerns the machine switching equipment, the transfer operation, in effect, may be said to correspond with the lifting of a telephone receiver from its switch hook on an instrument joined to an automatic system and equipped for automatically establishing telephone connections with other local stations or points, and in which, at such instant as switches may have responded and moved to such point as may render them ready for the reception of impulses from a dial at the instrument, an alternating current commonly referred to as dialing-tone will be impressed on the loop and manifested in the telephone receiver. In the present system, such dialing-tone current is translated by an alternating current relay in the switching paths already referred to, to place the loop circuit under control of the counting relays as further controlled by a system of stepping relays. Following release of a last impulse effect corresponding with any setting of the counting relays, a momentary impulse of alternating current will be released from the inward point to cause the counting relays associated with the distant numerical keys to release a next impulse of alternating current. Such cycle of operations may be repeated until the last impulse of a code series has been received from an originating point. Following this, the numerical keys and associated equipment will be automatically restored to normal and disconnected from the cord circuit, while the circuits at such point will be switched to the normal or talking position.

During the release of the devices at the outward point, a momentary impulse of alternating currents is sent over the line to effect re-transfer of the main conductors in joining the line to a loop circuit as established through machine switching equipment to the line of a station or point under call. Such circuit re-transfer also causes a momentary impulse of alternating current to revert over the main line and effect display of a supervisory signal to indicate to an outward operator that the connection has been completed to a distant point. On response at a called station an impulse of alternating current becomes effective to extinguish the supervisory signal while disconnect or replacement of a receiver on its

hook switch at a called point will cause the supervisory signal to be energized.

A connection may be retained until disconnection at an outward position takes place. This results in application of alternating current to the line for effecting restoral of the devices at a distant inward point. Due to such restoral, an impulse of alternating current will revert over the line to effect disconnection of the alternating current and restoral of the equipment of the line circuit at the originating position.

A preferred form of receptor or translator for the alternating currents employed in the present system, may comprise an electromagnetic device tuned to respond to alternating currents of a particular frequency. The device may be of the type employing an inertia element normally establishing a circuit in a manner to permit acceleration of this element under the influence of alternating current to disable the circuit. A device of this nature is shown in copending application Serial No. 526,152 filed December 31, 1921, (H. W. O'Neill), and for convenience, devices of this type have been shown and will be described for use in the present system.

This invention is illustrated in the accompanying drawings, in such a manner that when Fig. 1 is positioned above Fig. 2, Fig. 3 to the right of Fig. 1, Figs. 4 and 5 extending to the right of Fig. 2, with Fig. 6 below Fig. 5, a complete arrangement for carrying out the features of this invention will be diagrammatically illustrated.

In detail, Fig. 1 shows a digit keyboard associated with an outward toll operator's position;

Fig. 2 shows a group of counting relays associated with the digit keys of Fig. 1;

Fig. 3 shows a group of frequency selecting relays also associated with the digit keys of Fig. 1 at the outward operator's position;

Fig. 4 shows a portion of a cord circuit "C" at the outward operator's position, a calling subscriber's line A which may be associated with the operator's cord circuit in any well known manner, and outward equipment "D" of a toll line L;

Fig. 5 shows receiving equipment at the distant or incoming end of the toll line from which a trunk line L¹ extends to an automatic exchange of any well known type, and

Fig. 6 shows a system of selectable relays "E" and a group of counting relays "F" associated with the receiving equipment of Fig. 5.

Fig. 7 is a diagrammatic showing of a complete system by means of which a connection between a calling and called subscriber may be made in accordance with this invention. This figure shows calling

and called subscriber's lines, an outgoing operator's position, a toll line connected to an automatic exchange where a trunk line is shown terminating in automatic switches whereby a called subscriber's line may be reached.

Different frequencies of the alternating currents mentioned above may be of either low or high range, although definite frequencies have been assigned in the drawings to the various sources of alternating current.

In a more detailed description of the system for carrying out the features of this invention let it be assumed that a toll operator at an outward position (Figs. 1-4) has received a ticket in any well known manner, indicating that a connection is desired by a station A (Fig. 4) with a distant point or station of an automatic system (not shown), which station, for convenience of description, will be designated as Sterling 1590.

The digit keys (Fig. 1) have, for convenience, been designated in accordance with a well known system whereby the first three letters of the name of an office and the numerical digits corresponding with the exchange number of the called station may be "set up". In accordance with this system the code for the present assumed call will be represented by the digits S-T-E-1-5-9-0 which may be set up by depressing key 7 in the first or A row, key 8 in the second or B row, key 3 in the third or C row and keys 1, 5, 9 and 0 in the fourth or "Th" row, fifth or "H" row, sixth or "T" row and seventh or "U" row, respectively. The last three rows of keys correspond, as indicated, with station hundreds "SH", station tens "ST" and station units "SU", may be employed more particularly for reaching extension stations in a private automatic exchange, these keys will not be employed and therefore may be disregarded in the present assumed call. For the sake of clearness, the contact points of the keys assumed as now depressed have been shown in heavy or shaded marking. The depressed keys will lock in their actuated positions under control of a magnet 115.

A plug 401 may now be inserted into a jack 402 of a toll line L. This completes a sleeve circuit from grounded battery over the parallel connected local contacts of relays 405 to 408, key 409, upper contacts and upper winding of a polar relay 410, conductor 412, the sleeve contacts of the plug and jack to ground through the windings of relays 420 and 425. The latter relays now operate. Relay 425 operates in advance of relay 420 which is slow-to-operate and also slow-to-release. This prevents response of the relay 430 at this time.

The left hand contacts of relay 425 connect battery to a busy bus conductor 433 to oper-

ate busy signals 431 and 432 which may be assumed to be in association with multiple jacks at other positions of the switchboard, not shown.

Battery connected to the lead 433 also causes relay 435 to operate in a circuit which may be traced through contacts 436 of inward equipment 437 which is not shown in detail. Relay 435 in operating, switches the toll line L from the inward equipment 75 437 to the tip and ring spring members of the jack 402 by way of the upper and lower inner normal contacts of relay 430.

The purpose of the left hand contacts of the relay 420 in parallel with the left hand contacts of relay 425 is to momentarily continue the busy signals 431, 432 operated, following the removal of the plug 401 from the jack 402 as will be presently described.

It will be noted that the winding of relay 440 is shunted by a path which may be traced from grounded battery over the contacts of relays 405 to 408, key 409, and the upper alternate contacts of relay 410. Therefore, when the plug 401 was inserted in the 90 jack 402, a circuit was also completed from battery, over the contacts of relay 440, the winding of relay 445, lower winding of relay 410, the sleeve contacts of the plug and jack to ground through the windings of relays 420 and 425. Relay 445 operates in this circuit as established in parallel with the upper winding of the relay 410. The resistance of relay 445 reduces the current flowing through the lower winding of relay 410 to the extent that this current will not be sufficient to overcome the action of the stronger current in the upper winding of the relay 410. Therefore, the armature of the latter relay may continue on its upper bias.

Momentary depression of a key 446 will cause a relay 450 to operate in an obvious circuit. Relay 450 in operating, locks in a circuit from battery, the winding and lowermost alternate contacts of relay 450, conductors 453 and 254 to ground at the normal contacts of relay 230.

The upper and lower inner armatures of relay 450 when attracted, switch the right hand portion of the cord circuit C from the left hand portion to bus conductors 422 and 423 which extend over conductors 222 and 223 to a relay 240, Fig. 2, and over conductors 322 and 323 to frequency selecting relays 301 to 310, Fig. 3.

The uppermost contacts of relay 450 connect battery over a lead 451, to the sleeve strand of the cord independently of the contacts of relays 405 to 408 as a guard against possible premature effects on the signal 442. These contacts also supply battery over a lead 452 and the normal contacts of relay 240 to ground through the winding of a relay 223. The latter relay operates and connects ground to a conductor 242 thus completing

a circuit to light a pilot or master lamp 120 in an obvious circuit. Ground on the lead 242 also causes a first relay 201 of a first pair of counting relays 201 and 211 to operate in a circuit which may be traced from battery, conductor 243, winding of relay 201, lower normal contacts of relay 211, lead 242 to ground at the contacts of relay 225. Relay 201 in operating connects ground from bus conductor 253 to operate a frequency selecting relay 307 in a circuit which may be traced from battery, over conductor 333, the winding of relay 307, conductors 332 and 132, contacts of the digit key 7 of the first 15 or A row of keys Fig. 1, the upper normal contacts of relay 211, the contacts of relay 201, bus conductor 253 to ground at the lowermost normal contacts of relay 230. By means of mechanism, not shown, depression 20 of any digit key in any one of the vertical rows A to Su, Fig. 1, automatically separates and retains separated, the corresponding contacts in the horizontal row of contacts 101 to 110, until the respectively associated 25 key may be restored. It will therefore be clear that for the assumed call, the contacts 101 to 107 will be separated, while the contacts 108 to 110 will remain closed due to the fact that no keys have been operated in the 30 associated rows Sh, St and Su.

Relay 307 operates in the circuit just traced and connects alternating current of frequency f^1 supplied through a transformer 311 to the toll line L, to actuate correspondingly tuned relay 501, Fig. 5, at the distant end of the line. The circuit for this may be traced from ground, secondary winding of transformer 311, upper alternate contacts of relay 307, upper normal contacts 40 of relays 306 to 301, conductors 322, and 422 inner lower alternate contacts of relay 450, ring members of plug 401 and jack 402, inner lower normal contacts of relay 430, right-hand alternate contacts of relay 435, 45 contacts 536 of a relay not fully shown in the inward equipment 500, which may correspond with the relay 435 at the outward end of the line, the inner normal contacts of relay 505, the windings of tuned relays 501, 502, 503 and 504, conductor 521, uppermost normal contacts of relay 505, contacts 537 at the inward equipment 500, left-hand alternate contacts of relay 435, upper normal contacts of relay 430, tip members of 55 the jack and plug, the second uppermost alternate contacts of relay 450, conductors 423 and 323, lower normal contacts of relays 301, to 306, thence to ground through the lower alternate contacts of the relay 60 307 and a resistance 317. Relay 501 is the only one of the above group of four relays which may respond to the frequency of source f^1 . Therefore, while relay 501 responds to separate its normally closed con-

tacts, the relays 502 to 504 remain at rest 65 with their respective contacts closed.

In the normal position of the receiving circuits, Fig. 5, the following four circuits may be traced. A first path extends from battery, the left-hand winding of relay 510, 70 left-hand winding of relay 511, and contacts of relay 501 to ground. A second path from battery, middle winding of relay 510, left-hand winding of relay 512, right-hand winding of relay 511, and the contacts 75 of relay 502 to ground. A third path from battery, right-hand winding of relay 510, right-hand winding of relay 512, left-hand winding of relay 513, contacts of relay 503 to ground, while a fourth path extends from battery resistance 514, right-hand winding 80 of relay 513, and the contacts of relay 504 to ground. As indicated, the windings of relay 510 are connected accumulatively and therefore, this relay is normally operated, whereas the windings of relays 511, 512 and 513 are differentially connected, therefore, these relays will be normally unoperated. Relay 510 in its operated position connects 85 battery to a bus conductor 516. When relay 501 responded to the impulse of frequency f^1 previously mentioned, it opened its contacts and thus permitted relay 511 to operate under the current flowing in its right-hand winding as previously traced. While 90 relay 511 is operated, a circuit for the operation of relay 520 may be traced from battery, left-hand alternate contact of relay 510, right-hand alternate contacts of relay 511, conductor 517, upper middle, normal 95 contacts of relay 515, lower inner normal contacts of relay 520 and the winding of relay 520 to ground. Relay 520 operates and locks up in a circuit which may be 100 traced from battery, left-hand alternate contacts of relay 510, conductor 516, inner lower alternate contacts of relay 520 and winding of relay 520 to ground. The two uppermost sets of contacts of the relay 520 transfer the conductors of trunk L¹ from the line L to a bridge consisting of the winding 105 of alternating current relay 525 and the normal contacts of a relay 530. Direct current from automatic equipment, not shown, but which may be assumed as connected to the distant end of the trunk loop L¹ may now flow in the completed circuit through the winding of the relay 525 and normal contacts of the relay 530 to initiate, 110 at the distant machine switching office, the operation of equipment to result in the application to the trunk loop L¹ of alternating current, usually referred to as dialing tone. This is the usual signal to indicate that the 115 automatic equipment is positioned for the reception of impulses. While the direct current flowing back over the loop L¹ may be 120 ineffective to operate alternating current 125 re-

lay 525, the alternating current used to produce the dialing tone effects response of relay 525 to separate its contacts, thereby removing an obvious shunt path normally present around the winding of relay 535.

Relay 535 may now operate in a circuit from battery, alternate contacts of relay 510, conductor 516, inner lower alternate contact of relay 520, resistance 531, and winding of relay 535 to ground. Relay 535 in operating, removes ground from the contacts of relay 525 and connects ground over the upper normal contacts of relay 540, conductors 541 and 641, to the armature of relay 621. Due to battery being present on bus conductor 518 as already mentioned, a number of branch circuits may now be traced from its extension conductor 632. One path extends through the winding of relay 628, upper windings of relays 625 and 624, lower winding of relay 621 to ground through the contacts of relay 502. Another path may be traced from conductor 632 through the winding of relay 629, upper winding of relay 626, lower windings of relays 624 and 622, and to ground through the contacts of relay 503. Still another path may be traced from conductor 632, through the winding of relay 630, lower windings of relays 626, 625 and 623, to ground through the contacts of relay 504. Due to the fact that the tuned armature of relay 501 which carries the contact elements of this relay, is now under vibration due to the presence of alternating current from source f^1 as transmitted over the toll line from the outward equipment, the contacts of relay 501 will be separated thereby removing ground from a path which may be traced from conductor 632 through the winding of relay 627, upper windings of relays 623, 622 and 621, therefore, relay 627 remains unoperated at this time.

The connective relation of the windings on the double wound relays 621 to 626 is accumulative and therefore, these relays will be energized due to current flowing in the circuits just traced through the windings of the relays 628, 629, and 630. It will be clear, therefore, that continuance of the incoming alternating current over the line L from the source f^1 , may operate the tuned relay 501, and thereby effect operation of the relays 621 to 626 and 628 to 630 while the relay 627 will continue unoperated. Another circuit may now be traced from battery on the bus conductor 632, over conductor 633, winding of relay 607, upper normal contacts of relay 617, lower normal contacts of relay 627, alternate contacts of relays 626, 625, 624, 623, 622 and 621, conductors 641, and 541, upper normal contacts of relay 540, and alternate contacts of relay 535 to ground. Relay 607 operates in this circuit and substantially coincident therewith

relay 545 also operates in a circuit which may be traced from battery on conductor 518, through the winding of this relay, lower and upper normal contacts of relay 540, and alternate contacts of relay 535 to ground. Relay 545 in operating, completes a circuit for the energization of a relay 530 which may be traced from battery on conductor 518, winding of relay 530, contact of relay 535 to ground through the alternate contact of relay 535. Separation of the upper contacts of relay 530 opens the loop circuit of trunk line L¹ while closure of the lower contacts of relay 530 completes an obvious circuit for the operation of relay 540 from battery on conductor 518. The operation of relay 540 may be substantially simultaneous with the opening of the trunk loop. When relay 540 operates, it opens the circuit to release the relay 545. Relay 540 in operating, also opens at its upper contacts the ground connection to conductors 541 and 641, which connection up to this time, completed a shunt path around the winding of relay 617 of the seventh pair of counting relays. Relay 617 now operates in series with its mate relay 607, in a circuit from battery potential on conductor 633, winding of relays 607 and 617 and the contacts of relay 607 to ground on conductor 637. The release of relay 545 opens the circuit for relay 530 which now restores to normal and recloses at its upper contacts the loop including trunk L¹ and the alternating current relay 525. Relay 530 in releasing, also opens the energizing circuit for relay 540 which relay now releases to reconnect ground over the alternate contacts of relay 535 and the upper normal contacts of relay 540 to conductors 541 and 641, and to reoperate relay 545 in an obvious circuit. The first relay 606 of the sixth pair of counting relays may now energize in a circuit from battery potential on conductor 633, through the winding of relay 606 over the normal contacts of relay 616, alternate contacts of relay 617, normal contacts of relay 627, alternate contacts of relays 626 to 621, conductors 641 and 541, upper normal contact of relay 540 to ground at the alternate contacts of relay 545. Relays 545 and 606, the circuits of which have just been traced, respond substantially in unison, and a cycle of operations similar to those just described, may be repeated to cause the reoperation and release of relay 530 to again momentarily open and close the trunk loop, while relay 540 will be operated to permit the operation of the second relay 616 of the sixth pair of counting relays. In a corresponding manner, the above cycle of operations may be repeated in counting downwardly over the respective pairs of counting relays 605, 615; 604, 642; 603, 613; 602, 612; and 601, 611.

It will be clear from the foregoing that

when the relay 611 of the first or left-hand pair of counting relays, has responded the relay 530 will have been operated and released to effect seven impulses or momentary interruptions in the trunk loop L^1 . As will be understood by those familiar with automatic telephone systems, a first register or selector switch of an automatic exchange in which the trunk L^1 may terminate, may consequently have been advanced to a predetermined position. The operation of counting relay 611 at the conclusion of the seventh impulse to the line L^1 , connects ground over conductor 631 through the windings of relays 550 and 505 to battery. Relay 505 operates in the above circuit and transfers the conductors of line L from the receiving circuit which includes the serially connected receiving relays 501 to 504, to a source of alternating current f^5 supplied through a transformer 551 and the contacts of relay 550, which relay operated in unison with relay 505. At the outward end of the line L , Figs. 1, 2, 3 and 4, this current may complete circuit through the windings of relay 240 over a previously traced circuit including the upper and lower inner alternate contacts of relay 450. Relay 240 in responding to this alternating current from the source f^5 opens the circuit of relay 225 which releases and disconnects ground from lead 242, thereby extinguishing the lamp 120 and in breaking the shunt path around relay 211 of the first pair of counting relays, permits this relay to operate in series with the winding of its mate relay 201. This circuit may be traced from battery, over conductor 243, winding of relays 201 and 211, contact of relay 201, conductor 253 to ground at the normal contacts of relay 230.

Attention will be returned for a moment to the distant or incoming end of the line and an instant will be assumed as when relay 505 operated, to disconnect at its normal contacts, the relays 501 to 504 thus deenergizing relay 501 which was under vibration due to alternating current from source f^1 as already described. This reestablishes the circuit from battery through the left hand windings of relays 510 and 511 to ground through the normally closed contacts of relay 501. Relay 511 due to the fact that its two windings are differentially connected now releases and disconnects battery from conductors 517, 518, 632 and 633. Removal of battery from conductor 632 permits relays 621 to 626, 628 to 630, 601 to 607 and 611 to 617 to release. Relay 611, in releasing, opens the previously traced circuit for energizing relays 550 and 505, thereby disconnecting the source of alternating current f^5 from the toll line L while reconnecting the line to the receiving relays 501 to 504.

Cessation of the impulse of alternating current supplied from source f^5 over the toll line L to actuate relay 240 permits this relay to come to rest, thus closing its contacts to effect reoperation of the relay 225. Response of relay 225 restores ground to the lead 242, whereupon pilot lamp 120 will again be lighted, and this ground may now extend over the alternate contacts of relay 211 to the lower armature of relay 212. The relay 202 of the second pair of counting relays may now respond over a circuit from battery, on lead 243 through the winding of relay 202, the lower normal contacts of relay 212, and lower alternate contacts of relay 211, to ground over the lead 242 and the alternate contacts of relay 225. Relay 211 in disconnecting the lead to the first or A row of digit keys effects release of the frequency selecting relay 307 (Fig. 3). Relay 202 in operating, also completes a circuit in conjunction with the eighth digit key of the B row corresponding to the second letter T of the call being described, for the operation of a frequency selecting relay 308. This circuit extends from battery, winding of relay 308, conductors 234 and 134, key 8 of the B row, upper normal contacts of relay 212, the contacts of relay 202, conductor 253 to ground over the lowermost normal contacts of relay 230. Relay 308 operates in this circuit and connects alternating current from source f^2 through a transformer 312, to the toll line L to operate the corresponding tuned relay 502 at the other end of the line, in a similar manner to that already described for the operation of relay 501 in connection with the impulse from source f^1 .

During the interval between the disconnection from the receiving circuit, Fig. 5, of the first application of alternating current and reception of the second impulse, the trunk loop L^1 will remain closed through the upper normal contacts of relay 530, and it will be assumed that during this interval apparatus at the automatic office (not shown), will function in a well known manner to transfer the trunk loop L^1 to the next following register or to a next selector switch depending on the type of system with which the distant end of the trunk L^1 may be connected.

Operation of the relay 502 in response to the second impulse of current opens the circuit through the right-hand winding of the differentially connected relay 511, thereby permitting this relay to again operate and connect battery over its alternate contacts to the conductors 517, 518, 632 and 633. With battery connected to conductor 633, a circuit is completed for the operation of relays 621 to 627 and 629 to 630, the circuits for which are obvious and will not be described in detail. The operation of relays

629 and 630 perform no useful function at this time since the ground lead 641 is opened at the alternate contacts of relay 628 due to the fact that relay 502 is now energized 5 in response to the impulse of alternating current from source f^2 . Therefore, the circuit for relay 628 is now open at the contacts of relay 502. With relays 621 to 627 operated, and relay 628 released the operation 10 of relay 608 of the eighth pair of counting relays is effected in a circuit from battery, alternate contacts of relays 510, and 511, conductors 517, 518, 632, 633, winding of relay 608, normal contacts of relays 618 and 628, alternate contacts of relays 627 to 621, conductors 641 and 541, upper normal contacts of relay 540 to ground at the alternate contacts of relay 535. When relay 511 operated and connected battery to conductors 517 15 and 518, repetition of a cycle of operation similar to that already described may take place relative to successive response and release of stepping relays 545, 530 and 540 in rendering eight impulses effective with 20 the loop circuit L^1 . The counting relays 601-618, 611-618 performing their part in these operations in a manner similar to that already described in connection with the reception and translation of the first impulse of 25 current over the line L relative to setting up impulses in the trunk circuit L^1 . At the instant the relay 611 will have responded relays 550 and 505 will be operated to again connect the source of alternating current 30 f^3 to the line L . The operation of relay 505 again disconnects the relays 501 to 504 from the line L and thereby permits relay 502 to restore and effect release of differentially connected relay 511. Relay 511 in 35 releasing, disconnects relays 621 to 627, 629 and 630, 601 and 608, 611 and 628, in a manner similar to that already described in connection with translation of the first assumed impulse. The eight impulses transmitted 40 into the trunk loop L^1 , may in a well known manner, serve to advance the assumed automatic equipment another stage.

At the outgoing end of the toll line, the arrival of the impulse of alternating current returned over the line from source f^3 on completion of the above cycle of operations, causes relay 240 to be operated as before described to disconnect the relay 225 which releases and removes ground from 45 lead 242. Removal of ground from lead 242 extinguishes the lamp 120 and also opens the shunt circuit around the winding of relay 212 of the second pair of counting relays, and this relay may therefore operate 50 in series with its mate relay 202 in a circuit similar to that previously described for the first pair of counting relays. Relay 212 in operating disconnects at its upper normal contacts the circuit previously traced 55 for the relay 308 and transfers lead 242

through to the lower armature of relay 213. Cessation of the impulse of alternating current from source f^3 due to release of the relays 550 and 505 permits relay 240 to come to rest, thereby closing the circuit to 70 reoperate relay 225. Relay 225 again connects ground to lead 242, to relight the pilot lamp 120 and also effect response of relay 203 in initiating a cycle of operations similar to those above described. 75

The third key in the C row of digit keys is now in its actuated position for transmitting the third letter E of the assumed code, and closes an obvious circuit for energizing relay 303. Relay 303 in operating, simultaneously connects alternating current from sources f^1 and f^4 over the previously traced paths including the upper and lower alternate contacts of relay 450 to the toll line L . From the description already given it will 80 be clear that following the reception, at the sending station, of the next reverte impulse of alternating current transmitted back over the toll line from the source f^1 , after direct current impulses corresponding to the digit E of the assumed call, have been sent into the trunk L^1 , the counting relays, Fig. 2, will again advance the control circuits to permit alternating currents from 85 sources f^1 and f^2 to be simultaneously connected to the toll line L^1 over the alternate contacts of relay 301. This impulse will correspond with the depressed key 1 of the thousands "Th" row of the digit keys. In turn, key 5 of the hundreds row of digit 90 keys and relay 305 govern the simultaneous application of alternating currents from sources f^2 and f^4 to the toll line. Key 9 of the tens "T" row of digit keys and relay 309 apply current from source f^3 to the toll line, and key 10 of the units "U" row of digits 95 keys and relay 310 govern the application of current from the source f^4 to the line L .

For the present assumed call, no keys were depressed in the last three rows of 100 digit keys, therefore, following the reception of a reverte impulse from the source f^5 to permit of the units impulse of the assumed number and the disposal at the inward point, response of the counting relay 105 217 for advancing the control to the next pair of counting relays 208, 218, a circuit will be prepared for the energization of relay 230. This circuit may be traced from battery, winding of relay 230, key group 110 contacts 110, 109, 108, lower alternate contacts of relays 217 to 211 to conductor 242. On cessation of the incoming impulse from source f^5 in a manner similar to that already described, restoration of relay 240 and reoperation of relay 225 to apply ground to the lead 242 will result in response of the relay 230. The upper contacts of the latter relay apply 115 ground over a lead 244 to effect energization 120 125 130

of a relay 320, Fig. 3. Relay 320 in operating, simultaneously connects current from sources f^1 , f^2 and f^3 through the respective normal contacts of relays 301 to 310 and conductors 322, 422 and 323, 423 to the line L over the upper and lower inner alternate contacts of relay 450. Response of the relay 230 also disconnects ground from the leads 253 to release the counting relays 201-207 and 211-217 and the relay 450. Due to the slow-to-release characteristics of the relay 450 as indicated in the drawing, the impulse of alternating currents will be continued for a sufficient interval with the line L. The purpose of this impulse will presently appear.

When relay 450 releases, its uppermost contacts disconnect battery from the lead 452 thereby permitting relay 225 to release and apply ground over the lower inner forward contacts of relay 230, now momentarily retained due to its slow-to-release characteristics, to energize the key release magnet 115 which releases all the depressed keys and permits them to return to their normal positions. Final release of the relay 230 disconnects the relay 320 and the equipment of Figs. 1, 2 and 3 will then be at rest in normal positions. The release of relay 450 also transfers the tip and ring conductors of the toll line L from the bus conductors 322 and 323 of the frequency selecting relays 301 to 310 to the main conductors 456, 457 of the cord circuit.

Directing attention to the incoming end of the toll line L, and assuming an instant when the pulse of current consisting of the combined frequencies of source f^1 and f^4 corresponding with the setting of the third digit key in the row C, was received at the inward point, the correspondingly tuned relays 501 and 504 were actuated and opened the circuits through the left-hand and right-hand windings respectively of the relays 511 and 513, thus permitting these differential relays to be energized by the current flowing in their other windings. Relays 511 and 513 in operating, connect battery from conductor 516 to conductor 517, in energizing leads 632 and 633. Relays 621, 623, 624, 625, 628 and 629 respond in circuits which will be obvious from the foregoing descriptions. Relays 623 and 627 and 630 will remain deenergized due to the fact that their energizing circuits are open at the contacts of relays 501 or 504, which relays are now under response to the frequencies f^1 or f^4 incoming over the toll line. This combination of energized and deenergized relays of the group E permits counting relays 603, 613, 602, 612 and 601, 611 to be sequentially operated to transmit a series of three impulses into the trunk loop L following which, the usual impulse of current from source f^5 will be transmitted back over

the toll line L to release the thousands impulse formed of frequencies f^1 and f^2 to operate relays 501 and 502. The operation of relay 502 opens the circuit through the left-hand winding of relay 512, which relay then operates due to current flowing in its right-hand winding to ground over the contacts of relay 503. Relay 511 is not operated at this time as the contacts of both relays 501 and 502 are now open. Relay 512 in operating connects battery at its left-hand contacts over leads 517, 518, 632 and 633. Relays 629, 630 and 622 to 626 may now operate while relays 627, 628 and 621 remain deenergized as their circuits are open at the contacts of the relays 501 and 502, respectively. Relays 601 and 611 operate in succession as before, whereby a single impulse is transmitted over the trunk loop L¹. Current from the source f^5 is again transmitted over the toll line in the same manner as before to release the setting of the hundreds digit of the called number, which is represented by a combined impulse of current consisting of frequencies f^2 and f^4 simultaneously applied to the toll line, thus causing relays 502 and 504 to respond. With relays 502 and 504 operated, and relays 501 and 503 at rest, relays 511 and 513 will be operated to cause relays 621 to 624, 626, 627 and 629 to operate. Relays 625, 628 and 630 continue deenergized due to the fact that their energizing circuits are open at the contacts of relays 502-504, respectively. In this combination, relay 625 is the first effective relay relative to the counting relays F and, therefore, relays 605, 615; 604, 614; 603, 613; 602, 612 and 601, 611, will in counting downwardly transmit five impulses into the trunk loop L¹. After this an impulse reverts over the toll line from source f^5 to cause the transmission of an alternating current impulse corresponding to the tens digit of the called member. This impulse of current being supplied from the source f^3 causes relay 503 at the incoming end of the toll line to be actuated, whereupon relay 513 will operate. Relay 513 in operating, causes relays 621 to 628 and 630 to be operated while relay 629 will remain inert as its circuit is now open at the contacts of relay 503. In this combination, counting relays 601-609, 611-619 will sequentially operate to transmit nine impulses over the loop L¹. The impulse of current reverting from source f^5 over the toll line after transmission of the nine impulses will release the last or units digit 10 or zero digit of the assumed call. This selection is effected by the transmission of an impulse of current frequency f^4 applied to the toll line over the contacts of relay 310. At the incoming end of the toll line, relay 504 responds to this current and causes relay 513 to operate. Relay 513 connects battery

over its alternate contacts and conductors 517, 518, 632 and 633, whereby relays 621 to 629 will be operated, the relay 630 remaining deenergized due to the fact that its energizing circuit is now open at the contacts of relay 504. In this combination, the entire series of counting relays 601—620 become effective to release ten impulses into the trunk loop L^1 . This brings the operations to the point where the impulse of current reverted over the toll line from the source f^5 following the last or units series of impulses in the present assumed call, and which resulted, as already described, in restoral of the sending equipment at the outward position.

Assuming now the condition already described whereby the relay 320 may be operated in applying the composite impulse 20 formed of the frequencies f^1 , f^2 and f^3 to the toll line, response of the relays 501, 502 and 503, will be had. The relays 501, 502 and 503 disconnect the three windings of relay 510 which will release, while, due to disconnection of the circuit through the left-hand winding of relay 513, this relay may respond to battery, through resistance 514 and its right-hand winding to ground over the closed contacts of relay 504. With relays 30 510 and 511 released, relay 515 may respond in a circuit from battery, winding of relay 585, winding and lowermost normal contacts of relay 515, the normal contacts of relays 511 and 510 to ground. Relay 585 being 35 marginal, does not operate in series with the high resistance winding of relay 515. Relay 515, however, responds and locks up to ground at its lowermost alternate contacts, at the same time disconnecting the ground 40 supplied over the normal contacts of relays 510 and 511. In its operated position, the upper and lower inner alternate contacts of relay 515 complete a circuit to connect the polarized relay 565 in bridge on the conductors of the trunk line L^1 , and in attracting 45 its upper middle armature, it opens the connection between conductors 517 and 518 to prevent further application of battery to the leads 632 and 633 and the relays of group 50 E, Fig. 6. The purpose of the uppermost contacts of relay 515 will be described later.

When relay 510 released and removed battery from conductor 516, disconnection of the relays 520 and 535 took place. Relay 55 520, however, is slow-to-release in order that polarized relay 565 may be connected across the trunk before relay 525 is removed therefrom by the release of this relay 520. Such non-interruption of the loop circuit of the 60 trunk line L^1 insures retaining of the assumed automatic switches at the distant end of the trunk, as well understood in the art. When relay 520 releases, however, it connects the trunk L^1 through to the toll line 65 L. At this time, the polarity of the direct

current in the trunk loop L^1 may be such that the armature of relay 565 will be moved from its normal bias into a position to close its upper contacts. In this position of the armature of relay 565, a circuit will be 70 closed from battery, windings of relays 505 and 575, armature and lower contacts of relay 570, upper alternate contact and armature of relay 565, lowermost normal contacts of relay 520 to ground at the left-hand normal contacts of relay 585. Relays 575 and 505 operate in this circuit and apply as will be obvious, a composite impulse formed of frequencies f^1 , f^2 , f^3 and f^4 over the contacts of relays 575, and 505 to the toll line L. 75 Relay 505 in operating, connects grounded battery over its lower contacts, the lower winding of relay 570 thence over the circuit previously traced to ground at the left-hand contacts of relay 585. Relay 570 is of polarized type and the direction of this current is such that its armature will be moved out of engagement with its lower contacts and into engagement with its upper contacts. Separation of the lower contacts of relay 570 80 opens the energizing circuit previously traced for relays 505 and 575 and these relays now release and disconnect the alternating current of sources f^1 , f^2 , f^3 and f^4 from the toll line, and at the same time re-establishing the connection between the line L and the trunk L^1 which was broken during the interval that relay 505 was operated. 85 At the outward position, Figs. 1 to 4, this impulse of current causes relays 405, 406, 407, 408 bridged across the cord conductors 456, 457 to be operated. These relays in opening their contacts disconnect battery from the armature of relay 410 and thereby 90 discontinue the current through the upper winding of this relay as already traced. The current in the lower winding of relay 410 by way of the winding of relay 445, may now move the armature of this relay 410 95 against the action of the spring 411 out of engagement with its upper contacts and into engagement with its lower contacts. Cessation of the incoming impulse formed of four frequencies, permits restoral of relays 405—408 to reconnect battery to the armature of the relay 410. This results in the 100 shunting of relay 445 which on releasing establishes a circuit from grounded battery, normal contacts of relay 445, winding of relay 440, upper winding of relay 410, sleeve 105 contacts of the jack and plug to ground through the windings of relays 420 and 425. Relay 440 operates in this circuit and closes at its alternate contacts an obvious circuit 110 for lighting supervisory lamp 442. The strength of the current in the circuit through the upper winding of relay 410 is insufficient to attract its armature against the greater strength of current flowing in the lower winding of relay 410. It may be pointed 115 120 125 130

out that the slow-to-release characteristics of the relay 530 in delaying closure of its lower normal contacts, insures that the re-
5 vertive impulse of four frequencies will be present following release of the relay 450 and inclusion of the relays 405—408 with the line circuit.

Display of the signal 442 indicates that the assumed automatic equipment at the 10 distant end of the trunk loop L^1 has now extended the connection to the line of the called station, and, further, that such station is being signalled in a well known manner by ringing equipment located at the 15 automatic office.

When the called station answers, the ringing current may be disconnected and the 20 direct current in the trunk loop L^1 reversed in well known manner. Such reversal of current causes the armature of polar relay 565 to be moved to its opposite bias, that is, to the bias shown in the drawing. With the 25 armature of relay 565 in engagement with its lower contact stop, a circuit for the operation of relays 505 and 575 may be traced from battery through the windings of relay 505 and 575, armature and upper contact stop of polarized relay 570, lower contact 30 stop and armature of relay 565, lower normal contacts of relay 520, to ground at the left-hand normal contacts of relay 585. Relays 505 and 575 in operating, disconnect the 35 inward equipment and apply current from the four sources f^1 to f^4 to the toll line as previously described.

At the outward position, relays 405 to 408 respond to this current to separate their contacts thereby disconnecting battery from the armature of relay 410, which is now on its 40 lower bias, that is, with its armature in engagement with its lower contact. The armature of relay 410 may now move out of engagement with its lower contacts and into engagement with its upper contact, which 45 is the position in which the relay is shown in the drawing. When the incoming impulse of alternating currents ceases due to release of the relays 505 and 575 at the incoming end of the toll line as previously 50 described, relays 405 to 408 will come to rest, and in closing their contacts reapply battery to the armature of relay 410. This shunts the relay 440 and effects its release, thereby 55 extinguishing the supervisory lamp 442 and closing at the normal contacts of this relay a circuit to energize relay 445. This circuit extends through the lower winding of relay 410 as already traced. Relay 445 operates in this circuit but the current flowing in the 60 lower winding of relay 410 is not sufficient to overcome the effect of current in its upper winding. Disconnection of the lamp 442 indicates to the operator that the called station 65 has answered.

When relay 505 operated to connect the

impulse of current from the sources f^1 — f^4 to the toll line, the lower contacts of this relay connected battery through the upper winding of relay 570 to ground at relay 585 over the circuit previously traced from the 70 armature of relay 565. The direction of this current through relay 570 causes its armature to move to its opposite bias, that is, with its armature in contact with the lower contact stop, which is the position shown in 75 the drawing. This opens the previously traced circuit through relays 505 and 575 and these relays therefore release to disconnect the alternating current from the toll line L and reconnect the toll line to the 80 trunk loop L^1 extending to the called station.

As shown in the drawing the left-hand end of the cord circuit C is provided with a plug 454 adapted to be inserted into a jack 85 458 for the purpose of connecting the line of a calling subscriber as the line to the station A, which may now be considered as joined for conversation over the cord circuit with the assumed called station reached, 90 as described, over the toll or long distance line L . A key 455 serves for joining an operator's talking set (not shown) with the cord circuit.

When the conversation has been completed 95 and the called subscriber replaces his receiver on its switchhook, the current in the trunk loop L^1 is again reversed, whereupon relay 565 is operated to open its lower contacts and close its upper contacts, thereby 100 initiating another cycle of operations, whereby a momentary operation of relays 575 and 505 is effected to apply an impulse of current from the sources f^1 to f^4 to the toll line L . Relays 405 to 408 associated 105 with the cord circuit at the outgoing position respond to the currents of this impulse and momentarily remove battery from the armature of relay 410, thereby permitting this 110 relay to move its armature in the opposite direction to close its lower contacts due to the current flowing through its lower winding in series with the relay 445. When the 115 alternating current impulse ceases and relays 405 to 408 come to rest, battery will again be applied to the armature of relay 410, thereby shunting the relay 445, which 120 relay then releases and at its upper normal contacts reestablishes the circuit through the winding of relay 440 and the upper winding of relay 410. Relay 440 in operating energizes the supervisory lamp 442 which indicates to the operator that the called subscriber has disconnected.

In case the called subscriber may have 125 desired to attract the attention of the operator during the course of connection and therefore have flashed the switchhook in a well known manner, it will be understood from the description already given that when the 130

switchhook may have been in its upward position the supervisory lamp 442 would be extinguished and when the switchhook may have been in its downward position, the lamp 6 will have been lighted.

Assuming now that the lamp 442 is steadily lighted, thereby indicating that the called subscriber has replaced the receiver on its switchhook thereby indicating that the 10 conversation has been completed, the operator may remove the plug 401 from the jack 402, thus opening the circuit for relays 440, 410, 420 and 425. Relays 440 and 425 immediately release and after a short interval, the 15 slow-to-release relay 420 also releases. Relay 410 in deenergizing, permits the retractile spring 411 to move its armature to its normal position which is the position shown in the drawings.

20 During the interval between the release of relays 425 and 420 a circuit is completed to operate relays 430 and 340. This circuit may be traced from battery over the normally closed contacts of alternating current relay 25 465, right-hand alternate contacts of relay 420, right-hand normal contacts of relay 425, lowermost normal contacts and winding of relay 430, and the winding of relay 340 to ground. This effects response of the relays 30 430 and 340. Current from grounded battery over the contacts of relay 465 and the lower alternate contacts of relay 430, locks the relays 430 and 340 independently of the relays 420 and 425, under control of the 35 relay 465. The contacts 419 of relay 430 also apply this battery to the lead 433 for retaining the switching relay 435 and the busy signals 431 and 432 while a so-called "click" busy test condition will be maintained on the 40 sleeve or shell member of the jack 402 due to the presence of the condenser 471. Relay 430 in operating, opens its contacts 413 and 414 to disconnect the jack springs from the toll line L, at its contacts 415, 416, it connects 45 the toll line L to the windings of alternating current relay 465 and at its contacts 417 and 418 connects alternating currents from sources f^1 , f^2 , f^3 and f^4 as present over the contacts of relay 340 to the toll line. At the 50 inward equipment, Fig. 5, this impulse of currents causes the operation of relays 501 to 504, which in turn permits relay 510 to release due to the fact that the circuits through the three windings of this relay are opened 55 at the contacts of relays 501, 502 and 503. The operated condition of the relay 504 prevents response of the differential relay 513 at this time. Relay 510 in releasing, connects ground over its normal contacts and the normal contacts of relay 513 to short circuit the 60 relay 515, which relay may now release. This ground also forms a direct path for the relay 585 and permits it to operate. Relay 585 in operating, disconnects ground at its 65 left-hand normal contacts from the armature

of relay 565, and at its right-hand contacts connects ground to operate relays 550 and 505 in an obvious circuit. Relay 550 in operating, connects a momentary impulse of alternating current from the source f^5 to the 70 toll line in the same manner as before described, to effect operation of the relay 465 now connected to the toll line at the outward position. Response of relay 505 disconnects the relays 501 to 504 from the toll line, and 75 these relays therefore come to rest and close their contacts. This permits relay 510 to reoperate and disconnect ground and thereby deenergize relay 585. As shown by the drawing, this relay 585 is of slow-to-release 80 type and, therefore, relays 505 and 550 will be retained operated to permit the impulse of current from the source f^5 to be effective for a sufficient interval with the toll line L. When relay 585 releases, it disconnects 85 ground at its right-hand contacts, thereby disconnecting the relays 550 and 505, which relays may now release to disconnect the source of current f^5 from the toll line L and reconnect the line through to the trunk L¹. 90

When relay 465 at the outgoing position responded to the impulse of current from source f^5 , its contacts separated thereby releasing the relays 430, 340 and 435 the busy signals 431 and 432 and also removed the 95 click busy test condition from the shell member of the jack 402. Restoral of the relays 430 and 340 disconnects the four frequencies f^1 , f^2 , f^3 and f^4 and also the relay 465 from the toll line. It may be noted that the operating circuit for the relays 430 and 340 normally stands open at the right hand contacts of relay 420.

The retractile springs of the polar relays 410 and 565 insure that the armatures of these relays will normally be biased in the positions in which they are shown in the drawings, to insure so-called positive supervision by means of the supervisory lamp 442, that is, the supervisory lamp may be lighted 105 when response is had at a called point or station while the lamp may be extinguished when disconnect has taken place at such point. In case any irregularity of operation may occur and the lamp 442 should be improperly affected relative to its energization or deenergization, a momentary operation of the key 409 to remove battery from the armature of relay 410 suffices for correcting 110 the position of this signal.

At the inward equipment, Fig. 5, conductors 533 and 538 may be considered as corresponding with the busy conductor 433 and the lead 438 of the control circuit for the switching relay 435. It will be assumed 125 that equipment within a rectangle 500 may be in duplicate of the outgoing equipment of Figs. 1, 2, 3 and 4. During the period relay 520 may be operated in the processes of establishing a connection similar to that 130

just described, lead 533 will be disconnected from lead 538 at the upper inner normal contacts of relay 520 while the upper inner alternate contacts of this relay will apply battery to the lead 533 for establishing a busy condition at the outward equipment 500. After a connection has been established and during the talking period when relay 520 is deenergized and relay 515 operated, the upper transfer contacts of the latter relay serve to disconnect the lead 538 and to apply battery to continue a busy condition by way of the lead 533. This serves in the use of duplicate equipment at each end of the toll line in providing for two-way service thereover.

During the period relay 515 is operated, it breaks at its upper middle normal contacts the connection between conductors 517 and 518 to insure that subsequent operation of relays 501 to 504 will not affect relays 520, 530, 540 and 545, or the equipment of Fig. 6.

In case a busy condition of a station under call may be encountered the automatic equipment will become effective to establish reversals of current interrupted at a predetermined rate in the trunk circuit L^1 , as well understood in the art, to operate polarized relay 565. Such responses of relay 565 will cause supervisory lamp 442 to be alternately extinguished and lighted to indicate such busy condition to the operator who may thereupon disconnect by and release the automatic switches by removing the plug 401 from the jack 402 as already described.

In the operation of this system, a few seconds only suffice for permitting all the selective impulses required for establishing a connection. Therefore, it will be clear that the pilot lamp 120 will, in effect, be flashed as the lead 242 is successively advanced through the associated counting relays. Therefore, in the event that pilot lamp 120 should be steadily displayed, it will serve to indicate to the outward operator that irregularity is present.

From the foregoing description it will be clear that the inward equipment of the present system, shown in Figs. 5 and 6, may in general, be considered as a substitute for an instrument and calling device or dial of a subscriber station which may be connected for service through an automatic exchange over a circuit similar to the trunk L^1 .

It is generally the case that present day types of toll lines are opaque to direct currents, and, therefore, it will be clear that in this system, where the automatic equipment requires a direct current path such as trunk line L^1 , this trunk line must be open when disconnection is desired. To this end the release of relay 515, which is due as previously described to the removal of the plug 401 from the toll line jack 402, will result in opening the direct current path of the trunk

L^1 , to permit the automatic equipment assumed as connected thereto to release and restore to normal in the usual manner. Therefore, the circuits of the present system enable the originating toll operator to completely control the distant automatic equipment. Lines as employed in this system, afford a path for direct current from a circuit such as the trunk L^1 and may therefore have such means as condensers 547 and 548 interposed in the conductors of the toll line L as shown, to prevent flow of direct current over the toll line proper.

Relative to control of the supervisory signal 442, the purpose of the four alternating current relays 405-408 is to insure that voice or other currents may not become effective to result in translation of signals. A total of four definite frequencies being required before the signal 442 may be affected.

What is claimed is:

1. In a telephone exchange system, a toll line, automatic switching means associated with the incoming end thereof, a called subscriber's line terminating in said switching means, sources of alternating current, sending means for transmitting pulses over said toll line to set said switching means to connect said subscriber's line with said toll line, each of said pulses comprising currents from various combinations of said sources and means responsive to the first of said pulses to condition said switching means for receiving said pulses.

2. In a telephone exchange system, a toll line, automatic switching means associated with the incoming end thereof, a called subscriber's line terminating in said switching means, sources of alternating current, sending means for transmitting over said toll line a single pulse for each digit of the called subscriber's code to set said switching means, each of said pulses comprising currents from a certain combination of said sources, and means responsive to the first impulse of said code for conditioning said switching means for receiving said pulses.

3. In a telephone exchange system, a toll line, automatic switching means associated with the incoming end thereof, a called subscriber's line terminating in said switching means, sources of alternating current, sending means for transmitting over said toll line a single pulse of said current for each digit of the called subscriber's code to set said switching means, means responsive to the first pulse of said code for conditioning said switching means for receiving said pulses, and other means responsive to the conditioning of said switching means for translating said first pulse into direct current pulses to set said switching means.

4. In a telephone exchange system, a calling exchange, a called exchange, a toll line

extending therebetween, automatic switching means at said called exchange, a subscriber's line terminating therein, sources of alternating current, means at said calling exchange for transmitting over said toll line successive pulses of said alternating current corresponding to the code of the called subscriber's line to cause said switching means to connect said toll line with said subscriber's line, and means, responsive to the setting of said switching means in response to an impulse of said code, for transmitting an impulse of alternating current over the toll line to said calling exchange to release the next code impulse.

5. In a switching system, a line circuit, a plurality of alternating current sources, means for applying single impulses from said sources to said line, switching means for translating said single impulses into a plurality of impulses, and means responsive to a single impulse of alternating current for conditioning said switching means for the translation of impulses.

20 6. In a switching system, a first and a second point, a line intermediate said first and second points, switches for joining said second point to said line, means at the first point for applying successive impulses of alternating current to said line to control said switches, and means responsive in the control of said switches for effecting the release of said impulses of alternating current.

35 7. In a system for automatically joining remote telephone stations, automatic means for translating a single impulse into a plurality of impulses, switches controlled by said plurality of impulses, and means effective on a first response of said switches for rendering said plurality of impulses effective therewith.

40 8. In a system for transmitting impulses of alternating current, a line, a plurality of electroresponsive frequency selecting devices available to said line, switching means to render said devices effective to energize said line, when said line is associated with said devices, and electroresponsive means associated with the opposite end of said line for limiting the duration of the energization of the line.

45 9. In a system for automatically transmitting a succession of impulses of alternating currents, a line, a plurality of circuit control devices available to said line, means for rendering said devices effective to select alternating currents of various frequencies for energizing said line when said line is associated with said devices, electroresponsive means available to said line for successively rendering such selected currents effective with said line and other electroresponsive means associated with said line for

controlling said first mentioned electroresponsive means.

10. In a telephone system, an outgoing operator's position, a toll line terminating therein, a plurality of different frequency alternating current sources, a plurality of electroresponsive relays for selecting certain of said currents, electroresponsive means for successively applying said selected currents to the toll line, and other electroresponsive means associated with said toll line and responsive to alternating currents transmitted back over said toll line for controlling said first mentioned electroresponsive relays.

15 11. In a telephone exchange system, a toll line, a called station, a plurality of different frequency alternating current sources, sending means for transmitting over said toll line combined frequency pulses from said sources, tuned electromagnetic devices directly actuated by said pulses, and means controlled by said electromagnetic devices for establishing a connection between said toll line and said called station.

20 12. In a telephone exchange system, a calling exchange, a called exchange, a toll line extending between said exchanges, automatic switching means at said called exchange, a plurality of different frequency alternating current sources, means at said calling exchange for transmitting impulses from said sources over said line, and tuned electromagnetic devices actuated by said impulses for setting said switching means.

25 13. A telephone exchange system comprising an originating operator's position, a toll line extending therefrom to and terminating in receiving equipment, a trunk circuit extending from said receiving equipment to automatic switches, a called subscriber's station, a plurality of sources of alternating current of different frequency, sender means at said originating operator's position for sequentially transmitting over said toll line a single characteristic composite pulse of said alternating current for each digit of the called subscriber's number, and means associated with said receiving equipment comprising a plurality of tuned relays for translating each of said composite pulses into direct current impulses and for transmitting them into said trunk circuit to set said switches.

30 14. In a telephone exchange system comprising an originating operator's position, a toll line extending therefrom to and terminating in receiving equipment, a trunk circuit extending from said receiving equipment to automatic switches, a called subscriber's line, a plurality of sources of different frequency alternating current, sender means at said originating operator's position for sequentially transmitting over said toll line a single characteristic composite

pulse of said alternating current for each digit of the called subscriber's number, and means associated with said receiving equipment comprising a plurality of tuned relays each having a vibratory element and a loose contact member carried thereby for translating each of said composite pulses into direct current impulses of the proper decimal characteristic and for transmitting said direct current impulses into said trunk circuit for setting said switches into connection with said called subscriber's line.

15. A telephone exchange system comprising an originating exchange and a called exchange, a toll line extending therebetween, an automatic switch at said called exchange, sources of alternating current of different frequency, means at said originating exchange for simultaneously applying a plurality of said currents to the toll line in different combinations, and means at said called exchange comprising a plurality of tuned electromagnetic devices directly responsive to each of said different frequency

currents and a plurality of counting relays controlled thereby for setting said switch.

16. In a telephone exchange system, a first exchange, an operator's position thereat including a cord circuit and a supervisory signal device therefor, a second exchange, a toll line extending between said first and said second exchanges, a called subscriber's line extending from said second exchange, automatic switches at said second exchange for connecting said toll line with said called subscriber's line, a plurality of sources of different frequency alternating current, means at said second exchange for simultaneously applying said sources of current to said toll line when said automatic switch encounters a busy condition, and means at said operator's position including tuned electromagnetic devices directly responsive to said alternating currents to actuate said supervisory signal.

In witness whereof, I hereunto subscribe my name this 27 day of October A. D., 1923.

HENRY W. O'NEILL.
